CORNELIS HENRI CAALS, OF THE HAGUE, NETHERLANDS

FILTER CLOTH

Application filed November 22, 1926, Serial No. 150,156, and in the Netherlands April 26, 1926.

The invention relates to improved filter-cloths for use more particularly in filter-presses and to the improved filter-cloths produced according to this process.

5 Filter-cloths as at present used in filter-presses cannot be distinguished from ordinary textile fabrics.

When the filter-press is in operation and the plates are pressed together, the filter 10 cloths frequently wear out very quickly at those places where the plates meet, i. e. at the edges of the filter-plates. The worn out places cause the press to spout or leak and for this reason the filter-cloths have to be constantly under control and frequently mended.

15 It is the object of the present invention, to provide filter-cloths in which these drawbacks are eliminated and therefore the filter-cloths according to the invention are characterized by the feature that they have specially woven strengthening bands at those places, which correspond to the protruding edges of the filter-plates.

Figure 1 shows a filter cloth having heavy 20 warp and weft threads woven into the material at the points to be reinforced.

Figure 2 is a modified form illustrating a similar arrangement.

Figure 3 shows a filter cloth having a 25 greater number of warp and weft threads at the points to be reinforced.

In the drawing, Fig. 1 shows the warp threads *a a'* and weft threads *b b'* in which the warp and weft threads *a* and *b* are heavier 30 than the warp and weft threads *a' b'*. This gives zones of different strength in the cloth and a heavier strength at the border so that if cut on the lines 1—1 each piece will be reinforced at all its edges.

40 Figs. 2 and 3 show at *d* and *e* zones at which the warp and weft threads are spaced closer together than at the zone *f*. This gives the desired reinforced edges where the cloth is cut on the line 1—1.

45 Fig. 2 is an enlarged view of Fig. 3 showing at *g* where the warp threads are uppermost.

The strengthening bands are woven into the cloth by either warping and weaving 50 stronger threads or yarns at the desired

places or by increasing the number of warps and wefts at those places.

Although the corner-squares of the filter-cloths are of double thickness as compared with the side parts, it has been ascertained 55 that such difference in thickness does not cause any leakage and that the plates, when using the filter-cloths according to the invention, close up as narrowly as they would do when using any ordinary filter cloth and even 60 better because of the elastic tendency of the plates to bend out somewhat at the corners.

Another advantage of a filter-cloth according to the invention is that the central part may be woven independently from the 65 side-parts for example of a somewhat finer yarn number than would be possible with ordinary filter-cloth which needs must possess a definite minimal strength in the centre as well as at the sides. This involves 70 a quicker filtering of the material through the filter-cloths prepared according to the invention. In fact the centre of the filter-cloth according to the invention may be woven from a yarn which is quite different 75 from that which is used for the side parts and consequently yarns may be selected which will give the desired properties, viz., strength and quick filtering.

If for special purposes very strong yarns 80 or threads are woven into the borders, the plates or frames of the filter press may, if desired, be fraised out or grooved at the corners of these plates or frames may be provided with rubber parts which fit between 85 the corner-squares of the filter cloth. This measure is only taken when extra strong borders are desired.

It is also possible to let the yarn gradually increase in strength from the centre 90 to the sides of the filtering cloths.

In practice the process is carried out, for example, by weaving a continuous filter-fabric, warping the yarn to the desired strength and weaving after each centre a 95 double border, cutting the obtained fabric in the middle of each alternate double border so that a double filter-cloth with all round strengthened borders and a double strengthened border in the middle, to overlap 100

the top of the frames of the filter-press, is obtained.

Having now particularly described and ascertained the nature of my said invention and in what manner the same is to be performed, I declare that what I claim is:

A filter cloth adapted to be used between the frames of filter presses consisting of two central woven filtering portions and a circumambient strengthened woven marginal portion in the shape of a rectilinear figure 8, the central filtering portions being within the marginal portions and being separated by the intermediate transverse portion of said figure 8.

In testimony whereof I affix my signature.
CORNELIS HENRI GAALS.
